UNITED STATES PATENT OFFICE.

CALVIN M. ANDERSON, OF COLUMBUS, OHIO.

MACHINE FOR PRODUCING SPIRAL PUFFS.

1,369,723.

Specification of Letters Patent. Patented Feb. 22, 1921.

Application filed July 3, 1919. Serial No. 308,571.

To all whom it may concern:

Be it known that I, CALVIN M. ANDERSON, a citizen of the United States, residing at Columbus, in the county of Franklin and 5 State of Ohio, have invented certain new and useful Improvements in Machines for Producing Spiral Puffs, of which the following is a specification.

This invention relates to an improved 10 machine for producing spiral puff or gathering effects upon fabric materials, in order that the latter may be employed for suitable decorative purposes.

The object of the invention resides in the 15 provision of simple and effective means whereby a multiplicity of plaits or gathers may be produced upon a fabric layer of material in an effective, simple and expeditious manner, and to provide means in conjunction 20 with the machine for permanently retaining the effects produced upon the material.

With these and other objects in view as will appear as the description proceeds, the 25 invention accordingly consists in the novel features of construction, combination of elements and arrangements of parts hereinafter to be fully described and to have the scope thereof pointed out in the appended 30 claims.

In the accompanying drawing, forming a part of this specification, and in which similar characters of reference denote like and corresponding parts:

35 Figure 1 is a top plan view of a gather forming machine comprising the present invention, parts being broken away to disclose the underlying structure.

Fig. 2 is a fragmentary vertical sectional 40 view taken along the line 2—2 of Fig. 1.

Fig. 3 is a detailed transverse sectional view disclosing more particularly the manner of transmitting motion from one of said sections to an adjoining section.

45 Fig. 4 is a detailed perspective view of the upper end of one of the post members.

Fig. 5 is a perspective view of one of the braiding elements, and,

Fig. 6 is a detailed plan view disclosing 50 a layer of fabric material when formed with the spiral puff effects produced by the mechanism comprising the present invention.

Fig. 7 is a detail sectional view disclosing the completed connection between the spirally 55 puffed material and its lining.

In certain industries, it is desirable that

fabric material be gathered, Shirred or puffed to produce certain artistic effects, and heretofore this process has been largely effected by tedious hand work and which of necessity has involved considerable expense in effecting the production thereof. The present invention aims to produce a machine whereby these effects may be quickly and economically produced without detracting in any way from the general artistic and pleasing appearance of the same.

To this end the present invention contemplates the provision of a plurality of frames which are designated by the numeral 1. 70 These frames are of substantially rectangular configuration and are disposed to lie side by side and to be supported by means of parallel angle members 2, from which the frames are freely removable. The number 75 of frames employed is of course governed by the width of the material to be acted upon and therefore one or more frames may be utilized. Mounted for rotation upon said frames is a plurality of vertically up-standing posts 3, which are provided with lower circular portions and with upper square extremities 4, the latter projecting above the tops 5 of said frames. The upper ends of said posts are provided with spring elements 80 6, which are adapted to receive a plurality of prong members 7. The posts 3 are disposed in equally spaced relation and in operation a layer of fabric material to be acted upon is placed upon the upper squared ends 85 of the posts and in engagement with the prongs of the members 7, which latter are detachably but rotatably carried by the upper ends of said posts. By rotating the posts substantially a complete cycle of movement, the spiral puff 8 formed upon the material 9 is produced, and this effect is maintained by placing upon the material 9 a lining 10. Then by bending the prongs of the members 7 downwardly upon the lining, 90 the puff effect will thus be preserved. The material may then be removed from engagement with the posts by simply removing the prong members 7 from engagement with the spring holding device 6. It has been found 100 by practice that it is desirable to square the upper ends of the posts 3 in order that when the latter are rotated, the corners formed by the squared ends will engage with the material 9 and assist in imparting the necessary spiral movements thereto.

In order to simultaneously effect the rota-

tion of the posts 3, use is made of a gearing 11. This gearing may be one of many equivalent and obvious structures but for purposes of illustration, each of the lower ends 5 of the posts 3 is equipped with a gear 12, the latter being adapted for engagement with a plurality of alternately and reversely threaded worms 13 which are carried upon a longitudinally extending shaft 14 extending 10 centrally through each of the frame sections 1. It will be seen that by rotating the shafts 14, rotary movement in identical directions will be imparted to the posts 3 so that the latter may act upon the material 9 in the 15 above recited manner.

In order to rotate all of the shafts 14 simultaneously, each of said frames is equipped with a transversely journaled shaft 15, the latter being provided at one 20 end with a protruding squared extremity 16, and at its other end with a socketed portion 17, the portion 17 terminating within the frame 1 and in alignment with an opening 18 formed in the side wall of the frame. 25 Through this arrangement of parts, it will be obvious that a multiplicity of the frames may be associated in contiguous relation, and when thus associated the extremities 16 of their shafts 15 will project through the 30 openings 18 and into the socketed portion 17 of adjoining shafts. Thus, all of the transverse shafts will be connected for uniform rotational movement. Each shaft 15 is also provided with a worm 19, which is arranged 35 for meshing engagement with a coöperative worm gear 20 carried upon one end of the longitudinally extending shaft 14. In this manner the rotation of one of the transverse shafts 15 will effect simultaneous rotation 40 of all of the same, and their rotary movement, in turn, is imparted to the longitudinally extending shafts 14, and thence by means of the gearing 11 to the posts 3.

From the foregoing description taken in 45 connection with the accompanying drawing, it will be apparent that there is provided mechanism for quickly and efficiently producing artistic puff effects upon fabric or other similar materials, and the structure

is such as to enable the puff effects to be produced simultaneously over the full area of the material. Through the provision of the removable prong members 7, the puff effects may be permanently maintained and in this manner stitching is rendered unnecessary. 50 In practice it has been found desirable to produce the puff effects above described that the posts 3 should be given a substantially full rotational movement in order that said effects may be fully and completely produced. Through the arrangement of the sections, it is obvious that the latter may be adapted to materials of varying proportions. 55

I claim:

1. In a machine of the class described, a 60 base, a plurality of upright members rotatably carried in connection with said base, prongs mounted upon the upper portions of said members and arranged to penetrate and hold a sheet of loose fabric material placed 70 thereon in connection with said members, and means for revolving said members and prongs to produce decorative effects by twisting said material.

2. In a machine of the character described, 75 a base, a plurality of posts rotatably carried by said base, detachable prong members mounted upon the upper ends of said posts and capable of connecting loose fabric material with said posts, and means carried by 80 said base for revolving said posts and prong members to twist said material into a decorative form.

3. A gather forming machine comprising 85 a base structure, a plurality of posts rotatably carried by said base structure and projecting perpendicularly from the latter, prong members detachably carried by the outer ends of said posts and adapted to penetrate fabric material placed thereon, and 90 gearing mechanism operable to simultaneously rotate said posts and prong members in uniform directions, and to thereby twist said material into peculiar decorative formations.

In testimony whereof I affix my signature.

CALVIN M. ANDERSON.
